UNITED STATES PATENT OFFICE.

JOSEPH F. ROTHE, OF GREEN BAY, WISCONSIN.

GRATE.

1,117,249.

Specification of Letters Patent.

Patented Nov. 17, 1914.

Application filed October 3, 1910. Serial No. 585,000.

To all whom it may concern:

Be it known that I, JOSEPH F. ROTHE, a citizen of the United States, residing at Green Bay, county of Brown, and State of Wisconsin, have invented new and useful Improvements in Grates, of which the following is a specification.

My invention relates to improvements in furnace grates, and pertains especially to 10 that class of grates known as shaking grates.

The object of my invention is to provide a form of grate which will shake out the ashes with maximum efficiency and which will be less likely to become clogged with 15 clinkers than the ordinary grate.

In the following description, reference is had to the accompanying drawings, in which—

Figure 1 is a perspective view of a portion 20 of a furnace bed with my invention applied thereto, and showing portions of the grate bars and the depending shaking arms at one end, the wall of the bed being partially broken away to expose such arms and 25 the means for actuating them. Fig. 2 is a side view of one of the grate bars. Fig. 3 is a plan view of the same. Fig. 4 is a transverse sectional view, drawn on line 30 $x-x$ of Fig. 2. Fig. 5 is a plan view of a portion of the shaker bar.

Like parts are identified by the same reference characters throughout the several views.

My improved grate is formed with a 35 series of grate bars having a laterally curved sinuous web A, from which projections B extend on each side, these projections being in the form of laterally extending flanges or fins having upper surfaces b 40 adapted to support the fuel, and preferably rounded to some extent outwardly and downwardly from the web A. The lower portion of each of these flanges B tapers inwardly to the web, as best shown at a 45 in Fig. 4. Each of the grate bars is supported at its respective ends from bars C of the furnace bed frame, the grate bars having downwardly projecting point bearing members D loosely fitted to channel 50 sockets E in the frame bars C. The grate bar webs A are also provided near their respective ends with downwardly projecting arms F, whereby the grate bars may be oscillated upon said point bearing members 55 D by means of a shaker bar G and lever H.

Each of the shaker bars G is provided with projections I adapted to extend between the arms F of the grate bars. An auxiliary bar J is secured to the bar G by bolts K and bears upon the inner ends of 60 the projections F, the bar J being on the opposite sides of the arms F of the grate bars from that occupied by the bar G. With this construction, it is obvious that the arms F are loosely received, not only between the projections F, but between the bars G and J in such a manner that when the lever H is oscillated upon its pivot bearing K', the arms F will oscillate forwardly and backwardly, thus shaking the grate 70 bars. The bars G are mounted to slide in suitable bearings in the bed of the furnace.

Owing to the sinuous form of the webs A of the respective grate bars, it is obvious 75 that when such bars are oscillated, the portions thereof more distant from an axial straight line connecting the point bearings D will have a greater degree of movement than those portions of the grate bar which are located directly above said axial line. 80 It is also obvious that while the flanges B on the portions of the grate bar near the axis will have a simple oscillatory movement about said axis, the portions of the grate bar which are laterally offset from 85 such axis will lift upon one side and positively raise the body of fuel above such portions of the bar, while on the other side of the bar, the laterally offset portions will be simultaneously depressed. It will also 90 be observed that when any given portion of one grate bar is raised or depressed, the opposing portion of the adjacent bar will move in the opposite direction, these bars being thus rendered very effective for breaking 95 up portions of the fuel which tend to coke or fuse together.

The curves of each of the grate bars should correspond with those of the adjacent bars, but it is not essential to my invention whether the flanges or teeth B of one bar are directly opposite those of another bar or not. Preferably, however, they are arranged with the teeth of flanges B of one directly opposing the respective teeth 100 of the next bar. The specific form of the teeth is also not essential, although the form illustrated is preferred inasmuch as such teeth have great strength and while not 105 likely to catch and hold clinkers between 110

them, they exert great crushing power upon such clinkers as become caught between the teeth of one bar and those of the next.

Having thus described my invention, 5 what I claim as new, and desire to secure by Letters Patent, is—

1. The grate bar comprising a sinuous web provided along its upper margin with integral laterally projecting flanges constituting teeth, and having the upper portion 10 of said web extended at each end and provided with depending rocker bearing projections adapted to support said bar, substantially as described.
- 15 2. A grate comprising the combination of a series of parallel sinuous curved bars, each provided with integral oppositely pro-

jecting flanges along its upper margin, and having its upper portion projected at each end, integral bearing members depending 20 from the projecting end portions, integral operating arms depending from the lower portions of said web near each end, supporting members having sockets to receive said bearing members, and a sliding shaker bar 25 loosely engaging the operating arms, substantially as described.

In testimony whereof I affix my signature in the presence of two witnesses.

JOSEPH F. ROTHE.
